UNITED STATES PATENT OFFICE.

CHARLES GÜNSEL, OF NEWARK, NEW JERSEY, ASSIGNOR OF ONE-HALF TO
J. FREDERICK GÜNSEL, OF SAME PLACE.

CURTAIN-FIXTURE.

SPECIFICATION forming part of Letters Patent No. 416,600, dated December 3, 1889.

Application filed July 23, 1889. Serial No. 318,378. (No model.)

To all whom it may concern:

Be it known that I, CHARLES GÜNSEL, a citizen of the United States, residing at Newark, in the county of Essex and State of New Jersey, have invented certain new and useful Improvements in Curtain-Fixtures; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to improvements in curtain-fixtures illustrated in an application filed April 10, 1889, Serial No. 306,658, in which the shade-roll-supporting brackets are provided with an additional means for supporting a lace-curtain-holding pole.

The nature of the present invention is fully described in the following specification and finally embodied in the clauses of the claim.

Referring to the accompanying drawings, Figure 1 represents a front elevation of my improved curtain-fixture, illustrating the manner of attaching my device to the window-casing, and the shade-roll and the lace curtain-pole attached thereon. Fig. 2 is a similar view with the shade-roll and the pole detached therefrom to illustrate more clearly the arrangement of the supporting-fixture for arranging the whole device removably to the window-casing. Fig. 3 is a cross-section taken through line *x*, Fig. 1; and Figs. 4 and 5 are perspective views of a fastening-ring and the supporting-bar, respectively.

In each of the several views similar reference-letters are used to indicate like parts.

In said drawings, *A* represents the window-casing; *B*, a supporting fixture or bar, of wood or any other suitable material, provided with two or more eyes or rings *b* and *b'*, secured on said bar, and by means of which the latter may be hung to the hooks *a* and *a'*, which are driven into the top of the window-casing *A*, as shown in Figs. 1, 2, and 3.

On the bar *B*, at both ends thereof, are adjustably secured the shade-roll and curtain-pole holding brackets *c c*. Each of said brackets is provided at one end with a yoke *c'*,

conforming in elevation to the cross-section of the bar *B*, as in Fig. 3, the same thereby being adapted to slide on said bar and readily adjustable thereon to suit the length of any shade-roll, as has been indicated in Fig. 2 by 55 the positions of the brackets in dotted lines.

As has been stated in the above, the brackets *c* are fitted upon the bar *B*, and after having been adjusted to receive the curtain or shade-roll they are secured against the under side *b'* of the bar by means of the set-screws *c'*, the bar being preferably provided on the under side, at its ends, with metallic plates *b*, as illustrated more especially in Fig. 5, to avoid the marring or scratching of the lower side of the bar by the ends of the set-screws. The brackets *c* are provided with bearings *c*, of the ordinary construction, for supporting the shade-roll *d*. Extending out from the brackets beyond and slightly above the bearings *c* is an arm *c'*, provided at the end thereof with a U-shaped receiving portion *c*, consisting of the arms *c'* and *c*, into which the curtain-pole *e* may be placed, as shown in Figs. 1 and 3. Said pole is provided with rings *e'* 75 for attaching a lace curtain thereto, and at the free ends of the pole are arranged additional rings *e*, which are provided with set-screws *e* for securing the same to the pole *e*, and thus preventing the displacement of the 80 same out of its supports.

To prevent the pole *e* from turning in its supports or receiving portions *c*, the rings *e* may be provided with tongues *e* and *e*, which extend on both sides of the brackets *c* below 85 the U-shaped portion *c*, thus avoiding the turning of the pole within its supports.

The advantages derived from my invention are evident. The brackets are adjustably secured to the bar *B*, thus obviating the cutting and fitting of the shade-roll *d*, and also by the arrangement of the bar *B*, provided with means for hanging the same to the window-casing, I am enabled to remove the whole fixture from the window with very little trouble and without necessitating the removal of the curtains, poles, &c., from their supports. Furthermore, the bar *B* is made long enough so that the same will readily extend across any window, and when it becomes necessary 100

to apply the fixture to another window all that is required is to secure the hooks a and a' in the top of the window-casing and the fixture and its curtains are ready to be hung in place 5 on the window.

Having thus described my invention, what I claim is—

1. In combination with the bar B and means secured directly to the upper edge of 10 the said bar and extending up therefrom for hanging the same to a window-casing, metallic plates arranged on the under side of said bar, shade-brackets adjustably arranged on said bar by means of a set-screw which engages with said plates beneath the bar, means 15 formed integrally on said brackets for supporting a lace-curtain pole, and rings e^2 , on said pole, provided with outwardly-projecting tongues or stops thereon to prevent the 20 rotation of said curtain-pole in its supports, and a set-screw in each of said rings, arranged as and for the purposes set forth.

2. In combination with a bar B, provided with eyes b and b' for hanging the same to a window-casing, shade-brackets adjustably arranged on said bar and secured thereon by means of set-screws, said brackets having means thereon for supporting a shade-roll, arms c^4 on said brackets and extending up therefrom above said shade-roll supports, 30 and provided with a curtain-pole support c^5 , and rings e^2 on said pole, provided with tongues e^4 and e^5 thereon, and with set-screw e^3 , arranged substantially as and for the purposes set forth. 35

In testimony that I claim the invention set forth above I have hereunto set my hand this 22d day of July, 1889.

CHARLES GÜNSEL.
